UNITED STATES PATENT OFFICE.

ISRAEL ROSKIN, OF NEW YORK, N. Y.

FINGER RING.

Application filed November 18, 1925. Serial No. 69,750.

This invention relates to the manufacture of finger rings having settings or mountings for the display of precious ornamental stones and has for its principal objects the expeditious production of a ring of this character which is cheap, attractive in appearance and adapted to effectively display a stone when mounted therein.

I am aware that it has heretofore been proposed to construct a ring by first forming a plain skeleton annulus from a flat strip or by casting the said annulus and then soldering thereto a mounting, and therefore I do not broadly claim herein such

15 a ring or the method of making the same.

My invention is fully set forth in the following detailed description in which

20 Figure 1 is a developed plan of the inside of a blank or annulus employed in making my improved ring;

Fig. 2 is a side elevation of a blank or annulus; and

Fig. 3 is a similar view of the completed ring; and

25 Fig. 4 is a plan view of the ring shown in Fig. 3.

Referring to the drawings and the construction shown therein, the reference numeral 1 designates a ring blank or annulus, the same being either cast in a single piece or preferably formed from a flat strip of suitable metal as gold, silver, white gold, platinum or the like. The reference numeral 2 designates the top portion thereof which is formed between the shoulders 3, 3' and as shown, the top portion 2 is of an expanded construction having longitudinal marginal web members *a* and interconnecting web members *b* and *c* respectively. Preferably the shoulders 3, 3' and the expanded top are simultaneously formed by stamping out a suitable blank rod or bar shown in Fig. 1, the strip so produced is bent into an annulus as shown in Fig. 2 and the abutting ends are soldered or welded together at the point designated by the letter *e*.

50 A suitable superstructure 4, including a setting or mounting 5 of the desired configuration is applied to the annulus 1 by soldering the same on the top of the reticulated portion 2 intermediate the shoulders 3, 3' and, when a rare or ornamental stone is mounted in said mounting or setting, the light will enter the aperture *f* in the top of the setting of said superstructure through

the larger aperture *d* in the annulus without any obstruction being offered to its passage therethrough.

While the aperture *d* in the center of the portion 2 is relatively restricted in area, it affords, together with the slots formed between the cross web *b* and *c* and marginal webs *a* ample area for the passage of light through the portion 2 to the superstructure 65 and particularly to the setting thereof, while at the same time no serious obstruction is offered to the removal of the ring from a finger of a wearer to which it is properly fitted.

70 The reticulated portion 2 is considerably wider than the shanks which connect it to the annulus 1 and also said portion 2 is considerably thinner than such shanks, hence the same can be struck up from a strip of 75 metal of uniform cross-section throughout its length.

75 As is evident from the foregoing, the function of the reticulated portion 2 is to eliminate both the hollow fret work of the 80 housing and the bottom of the setting so as to more effectively display a stone mounting in such setting and also the ornamental fret work of the housing, but at the same time by virtue of the construction of such 85 reticulated portion there is a minimum of resistance offered to the movement of the ring on the finger.

While I have described a preferred embodiment of my invention, it is obvious that 90 various modifications within the scope of the appended claims may be made without departing from the spirit of my invention.

Having thus described my invention, what I claim and desire to secure by United States 95 Letters Patent is:

1. In a finger ring, the combination comprising an annulus having a flattened reticulated upper portion and a superstructure including a setting secured to the top of such 100 reticulated portion, the latter portion being relatively broad as compared with adjacent portions of the annulus.

2. In a finger ring, the sub-combination comprising an annulus having a flattened reticulated upper portion, terminal shoulders adjacent and oppositely disposed with respect to said reticulated portion, the latter portion having continuous opposing marginal webs and interconnecting cross-webs, 110 which latter afford guides to the finger of a wearer when the ring is moved thereon.

3. In a finger ring, the sub-combination comprising an annulus having a flattened reticulated upper portion, terminal shoulders adjacent and oppositely disposed with respect to said reticulated portion, the latter portion having continuous opposing marginal webs forming two sides of a central aperture and interconnecting cross-webs, which latter afford guides to the finger of a wearer when the ring is moved thereon.
4. In a finger ring, the combination comprising an annulus having a thin, wide, flattened reticulated portion and relatively thick

shank portions on either side of such reticulated portion; shoulders at the respective ends of such reticulated portion, a superstructure including a setting permanently secured to the top of the reticulated portion and said latter portion and said superstructure having registering central apertures serving as windows for the admission of light to the bottom of the setting.

Signed at New York, in the county and State of New York, this 14th day of November, 1925.

ISRAEL ROSKIN.
